J. R. Littell,

UNITED STATES PATENT OFFICE.

MARTIN L. SCHOCH, OF NEW BERLIN, PENNSYLVANIA.

SPOON.

SPECIFICATION forming part of Letters Patent No. 461,623, dated October 20, 1891.

Application filed December 27, 1890. Serial No. 375,986. (No model.)

To all whom it may concern:

Be it known that I, MARTIN L. SCHOCH, a citizen of the United States, residing at New Berlin, in the county of Union and State of Pennsylvania, have invented certain new and useful Improvements in Spoons; and I do hereby declare that the following is a full, clear, and exact description of the invention, which will enable others skilled in the art to which it appertains to make and use the same.

My invention relates to spoons and embodies an improvement on Letters Patent No. 439,432, granted to me October 28, 1890.

The object of my present invention is to simplify the construction, and consequently decrease the cost of manufacture, of the device. As set forth in said patent and equally applicable to the improvement herein described, the spoon is provided with a removable attachment, by which all substance adhering to the spoon-bowl may be quickly and easily removed without the use of an additional implement to attain this result; and with this end in view my present improvement consists of the construction and arrangement of parts hereinafter more fully set forth.

In the accompanying drawings similar letters of reference are used to indicate corresponding parts in the several views, and

30 therein—

Figure 1 represents a perspective view of a spoon embodying my improvement and showing the scraper in the act of being moved over the bowl of the spoon. Fig. 2 represents a 35 bottom plan view of the spoon. Fig. 3 represents a cross-sectional view of the handle looking in rear of spoon-bowl.

Referring to the drawings, the spoon A may be of usual construction, but, as shown, is 40 more nearly scoop shape, being provided with a bowl or scoop A' and a handle A². A tube B is suspended from the back side of the handle near the end thereof, said tube being constructed from a piece of sheet metal bent into 45 tubular form at its central portion and having side flanges secured to the handle A²; or, if desired, the tube and handle may be made in one piece. Depending from one of the flanges, or thereabout, is a hook C, to which is movably 50 connected an elastic tension device D, consist-

ing, preferably, of a round rubberband. While this hook C is a substantial and convenient form of attachment, it is obviously apparent that any well-known mechanical equivalent may be readily substituted therefor. A rod 55 E projects rearwardly from the bowl A' and is formed with a knuckle or bend E', which extends beyond the edge of the handle to form a finger-piece. At a point ahead of said knuckle or bend E' the said rod is also formed with 60 an upward bend E², to which the elastic tension device may be connected, if desired. To construct this bend E² without detracting from the utility of the rod, said rod is gradually inclined downward, as at E³, from the 65 rear end of the bowl A'. The said rod terminates in a straight portion E⁴, which is freely mounted in the tube B, and as said rod is impelled forward and retracted the said portion E⁴ thereof has a continuous bearing 70 in said tube.

To regulate the distance of forward movement of the rod E, a projection or stop F is secured to the handle A² at a predetermined distance and against which the knuckle or 75 bend E' is adapted to strike.

The front portion of the handle A² and the rear portion of the bowl or scoop A' are formed with a slot G, through which the rod E has movement, and said slot is lengthened downward into back of bowl, so that after detaching the elastic tension device D from the rod E the said rod may be drawn therethrough and be thus removed from the spoon.

The front end of the rod E is bent downward and secured to the rear side of a scraper H, which fits closely in the spoon-bowl A', and has a lower bent edge H' to closely fit the bottom of said spoon-bowl to thereby entirely discharge any or all material sticking to this 85 portion of the bowl. It will be seen that when the rod E is drawn through slot G, as heretofore referred to, it also removes the scraper H from the spoon-bowl, thereby entirely disconnecting the attachment from the 90 spoon.

The scraper H is intended to lie flat against the back of the spoon-bowl A' and be fastened to rod E in such manner as to fit closely 95 between the top of the slot G and the bottom 100

of the bowl. As the rod E is inclined or bent downward, as at E³, it stands on almost a parallel line with the bottom of the bowl, and thereby the scraper H will be kept pressed against said bottom of the bowl by the pressure exerted on the rod E as it moves through the portion of the slot G in the handle A².

It will be understood that in removing the rod and scraper from the spoon, after detachment of the tension device D, the knuckle or bend E' of said rod may be pressed over the projection or stop F.

In operation the rod and scraper are pushed forward by hand and retracted by the tension device D, and the parts are so adjusted that the scraper will move over the entire surface of bowl or scoop A' and yet be prevented from extending beyond the end of said scoop or bowl by the projection or stop F being engaged by the knuckle or bend E' of the rod E.

The removability of the attachment from the spoon so readily and easily in the manner hereinbefore set forth adapts it to be used as a common spoon, even for liquids, as the slot G does not extend lower down than the top of the sides of the bowl. The simplified form of construction also renders the device more durable.

30 The device is adapted for use in connection with any material, but is more especially intended for lifting or otherwise handling ice-cream and substances of a similar nature.

Having thus described my invention, what I

claim as new, and desire to secure by Letters 35 Patent, is—

1. In a spoon, the combination, with the bowl slotted at its rear end, of the handle slotted at its forward end, a tube secured to the under face of the handle near its rear end, 40 the movable scraper arranged in the bowl, and the rod attached thereto, passing through the slots in the bowl and handle and working beneath said handle, the rear end of the rod working in the tube, said rod being formed 45 with a laterally-projecting extension intermediate its ends, said extension projecting beyond the sides of the handle, substantially as shown and described.

2. In a spoon, the combination, with the 50 slotted bowl and handle, of the tube secured beneath the rear end of the handle, the pin secured thereto, the stop-pin secured to the under side of handle near the forward end, the movable scraper, and the operating-rod 55 working through the slots beneath the handle and in the tube, said rod being provided with a lateral extension and an elastic connecting device connecting the rod and pin on the tube, substantially as shown and de- 60 scribed.

In testimony whereof I affix my signature in presence of two witnesses.

MARTIN L. SCHOCH.
